UNITED STATES PATENT OFFICE.

RUFUS KING, OF PLAINVILLE, MASSACHUSETTS, ASSIGNOR TO BUGBEE AND NILES COMPANY, OF NORTH ATTLEBORO, MASSACHUSETTS, A CORPORATION OF MASSACHUSETTS.

CLASP FOR STRAPS, BANDS, OR RIBBONS.

1,372,299.

Specification of Letters Patent. Patented Mar. 22, 1921.

Application filed June 14, 1919. Serial No. 304,149.

To all whom it may concern:

Be it known that I, RUFUS KING, a citizen of the United States, residing at Plainville, in the county of Norfolk, State of 5 Massachusetts, have invented certain new and useful Improvements in Clasps for Straps, Bands, or Ribbons, of which the following is a specification.

My invention is an improved clasp for 10 fastening the straps, bands or ribbons of wrist-watches or for similar uses. The object of my improvement is to provide a simplified device for this purpose which may be more easily and conveniently clasped and 15 unclasped, and which will fasten the band in place with greater security. Further objects of the improvement are to provide a clasp which is neat and ornamental in appearance; stanch and durable in use; and 20 easier and more economical to manufacture.

The manner and means for carrying out these improvements are fully described in the following specification, illustrated by the 25 accompanying drawings, in which like reference characters designate like parts. In the drawings:

Figure 1 is a view showing the two co-operating parts of my improved clasp applied to the wrist-band or ribbon;

Fig. 2 is an enlarged plan view of the 30 main clasp-member;

Fig. 3 is a side view of the same;

Fig. 4 is a sectional view taken in a vertical plane through both clasp-members, and 35 showing the latter in engaged relation;

Fig. 5 is an enlarged plan view of the slotted bottom-plate of the upper clasp-member; and

Fig. 6 is an end view of the lower, coöperating clasp-member.

Referring first to Fig. 1, my improved clasp or fastener comprises upper and lower coöperating parts; the main member C being adapted for fastening to the looped end 45 of the band or ribbon R, and the under slide S being formed to embrace the ribbon R and provided with spring-tongues for insertion through a slot in the upper member.

As shown more particularly in Figs. 2, 3 50 and 4 the main clasp-member C is constructed in two pieces consisting of a flat plate P formed with a loop or bail p at one end around which the end of the ribbon R is looped; and a top-shell or back D having 55 its rim crimped or rolled over the edges of

the plate P to fasten it in superimposed position thereon. Fig. 5 shows the plate P in detail as cut away or slotted at one end to provide the cross-bar or bail p, and slotted laterally at u to provide the opening for receiving the tongues t-t of the other clasp-member S. The sides of the slot u are somewhat convex or bowed outwardly toward each other for a purpose as later explained, and it will be noted from Fig. 5 that the opposite, lateral edges of the plate P are formed with V-shaped notches v-v into which the edges of the rim of the shell D are turned to provide a more finished joint. As shown in Figs. 2, 3 and 4, the shell D is 70 of rectangular outline with its top formed flat, but it may have a convex or crowned shape if preferred. Referring particularly to Figs. 3 and 4, the marginal rim d takes a bevel shape around the top panel of the 75 shell D, to enhance its artistic appearance, and the lower marginal edge of the rim is rolled over the edge of the under plate P on three sides as shown at d' in Fig. 4. At points adjacent the bail P the ends of the 80 rim d are turned into the notches v-v so as to prevent rough edges, see Fig. 1. On the fourth side of the plate P the rim d is cut away at its ends and fitted to a slot p' cut into the edge of the plate opposite the 85 bail p.

Referring now to Figs. 1, 4 and 6 the slide-member S is constructed from sheet-metal in the form of a flat plate of rectangular outline, and is punched out to form 90 side-strips s-s connected by opposite, lateral end-bars s'-s' and a central cross-bar e. The metal strips cut away from between the cross-bars s'-s' and e are bent upwardly in two parallel, spaced tongues t-t which 95 serve as the spring-detents for fastening the two parts of the clasp together. As shown more particularly in Figs. 4 and 6 the tongues t-t are slightly crimped along their sides or bowed inwardly toward each other to provide opposite detent-shoulders or ledges l-l which snap across the edges of the slot u in the plate P to hold the parts together. The upper edges of the tongues t-t are rounded or beveled off to 100 render them easier of insertion through the slot u in the plate P.

The manner of applying my improved strap to use is as follows: Referring to Fig. 1, the end of the band or ribbon R is dou- 110

bled around the end-bar or bail *p* which projects from the side of the clasp-member *C*, and the loop is then sewed or otherwise fastened together to attach this part of the 5 clasp in place. The opposite end of the ribbon *R* is then inserted through the slide *S* by passing it over the end-bars *s'-s'* and under the central bar *e*. This provides that the slide *S* may be slid along the ribbon to 10 adjust the length of the band in fastening it around the wearer's wrist, but when the band is drawn tight the slide will be prevented from moving on the ribbon. The end of the band or ribbon *R* opposite from the 15 clasp *C* is usually provided with a loop or other means for fastening it to a lug or ear on the watch while leaving the clasp-end free. This latter end is inserted through the opposite lug on the watch and is then turned 20 back and clasped to the slide *S* after the latter has been adjusted in position to draw the band tightly around the wrist.

In clasping the two members *C* and *S* together it is only necessary to register the 25 tongues *t-t* on the slide *S* with the slot *u* in the bottom plate *P* and to press the two parts together. The tongues *t-t* will thus be caused to spring together to enter their rounded ends through the slot *u*, and the 30 detent-shoulders *l-l* will snap into engagement with the edges of the slot to hold the parts together. In this way the two parts of the clasp are securely fastened together against lateral or longitudinal movement, 35 while to unclasp the device it is only necessary to pry the member *C* upwardly with the finger nail. This action causes the tongues *t-t* to be sprung together to release their shoulders *l-l* from the sides of the slot *u*, and thus when either fastening or unfastening the clasp only a single simple movement of the hand is required. The convex form of the sides of the slot *u* in the plate *P* renders it easier to enter the spring-tongues *t-t* through the slot and also tends 40 to provide a better engagement between the parts to prevent lateral displacement thereof.

It will be observed that when the two 50 parts of the clasp are fastened together the shell or back *D* of the member *C* completely covers the slide *S* and conceals the fastening-means. Moreover, the two parts are relatively flat and in their clasped relation 55 fit closely together so as to provide a particularly neat and unobtrusive appearance without the bulky or clumsy effect of the usual devices of this kind. The smooth, beveled edges of the upper member *C* heighten the ornamental appearance of the 60 clasp, and it is to be particularly noted that there are no sharp corners or projections to catch in the garments of the wearer. As illustrated in Fig. 2, the artistic effect of the 65 top of the clasp is heightened by an orna-

mental border *z*, and its central panel may be further embellished with scroll-designs or initials engraved thereon. The complete device, while being neater and more ornamental in appearance than the usual clasp, 70 is much simpler in construction, comprising a minimum number of parts which are struck up from sheet-metal, without requiring soldering, thereby tending to reduce the cost of manufacture. 75

Various modifications might be made in the form and structure of the parts of my improved clasp without departing from the spirit or scope of the invention, therefore, without limiting myself to the exact embodiment herein shown and described, what I claim is:

1. In a clasp for straps, bands or ribbons of wrist-watches, or for like purposes, the combination of a slide adapted for adjustment on the ribbon and provided with upstanding laterally-extending parallel spaced-apart strips forming spring-tongues having detent-shoulders on their sides, of a top-member provided with an extended slot 80 through which the tongues on the slide may be inserted to engage their detent-shoulders with the edges thereof.

2. In a clasp for fastening the ends of straps, bands or ribbons, the combination 95 with a member provided with upstanding opposite parallel spring-tongues having detent-shoulders on their sides, of a plate-like member formed with a slot adapted to be snapped over the spring-tongues to engage 100 its sides with the shoulders thereof, and a hollow shell having its marginal edges bent down around the edges of the plate-member to secure it in superimposed position thereon.

3. In a clasp for fastening the ends of 105 straps, bands or ribbons, the combination with a slide having opposite end-bars and a central cross-bar over and under which the ribbon leads, said central bar formed with integral upstanding parallel spring-tongues 110 extending along its sides and having detent-shoulders on their opposite sides, of a plate-member provided with a lateral slot adapted to receive the spring-tongues with its edges engaged by the detent-shoulders. 115

4. In a clasp for fastening the ends of straps, bands or ribbons, the combination of a plate-member formed with a relatively narrow slot having opposite convex sides, and a second coöoperating member having 120 upstanding parallel spring-tongues formed with opposite detent-shoulders, said spring-tongues adapted for insertion through the slot of the plate-member to engage their shoulders with its convex sides in the manner and for the purpose substantially as described.

In testimony whereof I affix my signature.

RUFUS KING.
